United States Patent Office

Des. 196,817
Patented Nov. 5, 1963

196,817

DISPENSING CONTAINER

Paul A. Marchant, Kansas City, Mo., and James B. Swett, Barrington, R.I., assignors to Rexall Drug and Chemical Company, Los Angeles, Calif., a corporation of Delaware

Filed Mar. 11, 1963, Ser. No. 73,919

Term of patent 14 years

(Cl. D58—17)

FIG. 1

FIG. 3

FIG. 2

The essential features of our design reside in the portions shown in full lines.

We claim:

The ornamental design for a dispensing container, as shown and described.
